D. R. BAKER.
Signal for Water-Closets.

No. 224,125.

Patented Feb. 3, 1880.

UNITED STATES PATENT OFFICE.

DELOS R. BAKER, OF CINCINNATI, OHIO.

SIGNAL FOR WATER-CLOSETS.

SPECIFICATION forming part of Letters Patent No. 224,125, dated February 3, 1880.

Application filed August 22, 1879.

To all whom it may concern:

Be it known that I, DELOS R. BAKER, of Cincinnati, Hamilton county, State of Ohio, have invented certain new and useful Improvements in Signals for Water-Closets for Railroad-Cars and other Places, of which the following is a specification.

Referring to the drawings, Figure 1 is a sectional elevation of a railway-car water-closet embodying my invention. Fig. 2 is a perspective view of my invention in detail.

My invention has for its object to indicate by signal the occupancy of the water-closet, so that a glance will sufficiently inform persons of the fact without necessitating their trying the door, the embarrassment attending which method being well understood and appreciated, especially by ladies, in railway-cars and other public places.

To this end my invention consists in the arrangement of a shifting signal in suitable connection with a movable floor in the closet, so adapted as that thereby the weight of the occupant of the closet will operate to display the signal, the details of construction being fully described hereinafter.

On reference to the drawings, A represents, for the purposes of illustration, the water-closet of a railway-car, having the usual commode-seat *a* secured to the floor *B* thereof. This floor is hinged at *b*, and its free end rests upon spring-buffers *C*, and is provided with an arm, *b'*, to engage with a horizontal lever, *D*, pivoted at *d* to a lug upon the car-sill.

The extreme end of the lever *D* is secured to a vertical rod, *E*, which moves in guide *e*, and carries at its upper extremity a signal board or disk, *F*. The rod *E* and signal-board *F* are located inside the water-closet close to the partition or wall *G*, and they are concealed from view by boxing *H*, as seen in Fig. 1.

The guide *e* is secured to the partition *G*, and the signal *F* thereby held in close proximity to the said partition, where it may shift back and forth behind the opening *g* therein. The side of the signal-board which faces the opening *g* is divided into two contrasting parts, one of which harmonizes with the color of the partition *G*, and when before the opening *g* serves to hide or obscure it, while the

other contrasts with the color of said partition, and when before the opening forms a conspicuous object for the eye to rest upon.

When a person takes possession of the closet his weight acts upon the floor to compress it, and motion is thereby communicated through *b'*, lever *D*, and rod *E* to signal-board *F*, which falls so as to display the contrasting color through opening *g* and constitute a signal. When the occupant leaves the closet the floor, being relieved of the weight, rises by virtue of the spring-buffers *C*, and communicates motion through arm *b'*, lever *D*, and rod *E* to the signal-board, which then rises so as to display the harmonizing color through the opening in the partition and mask or obscure the signal.

Thus it will be seen that the occupancy of the closet will be indicated by the display of the contrasting color of the signal-board through opening *g*, and its vacancy will be indicated by the presence of the harmonizing color of the signal-board behind said opening.

In the matter of structural detail, the boxing around the rod *E* extends somewhat below the floor *B*, so that the downward movement of the latter will not expose the said rod to injury by accident or otherwise.

As shown, the buffers *C* consist of coiled springs secured in sockets *c* on the sill of the car; but other forms of springs may be found desirable, and the spiral springs, if used, may be strained and secured to the sockets by centrally-secured bolts.

The floor is represented as hinged; but it is obvious that it may be supported wholly by springs, if so desired.

In order to reduce the necessary movement of the floor to a minimum, and at the same time secure sufficient movement of the signal, the arm *b'* is connected to lever *D* near its pivotal point, and the rod *E* secured to it near its outer extremity or point of greatest movement.

In conclusion, it is evident that the mechanism for transmitting motion from the floor to the signal may be varied greatly. The signal may be itself greatly altered in style and method of operation, and the invention, as a whole, may be applied to other compartments.

than water-closets. I do not therefore wish to limit myself to any special construction or application.

I therefore claim—

- 5 1. In combination, a signal, a movable room-floor, and suitable mechanism whereby the weight of a person upon the floor will operate to expose the signal, substantially in the manner and for the purpose specified.
- 10 2. In combination with a movable room-floor adapted to operate a signal by the weight of the occupant, the spring-buffer C, arranged to return the floor to a normal position, substantially as and for the purpose specified.

3. In combination, a hinged room-floor, 15 spring-supporting buffers, a signal, and connecting-levers, all arranged substantially in the manner and for the purpose specified.

In testimony of which invention I hereunto set my hand this 19th day of August, A. D. 20 1879.

DELOS R. BAKER.
